CLAIM

The ornamental design for a kitchen implement handle, as shown and described.

DESCRIPTION

FIG. 1 is a front, perspective view of a kitchen implement handle showing a first embodiment of our new design; FIG. 2 is a front view thereof, rear view being a mirror image of the front view;

FIG. 3 is a right side view thereof, the left side view being a mirror image of the right side view;

FIG. 4 is a top view thereof; and

FIG. 5 is a bottom view thereof.

FIG. 6 is a front, perspective view of the kitchen implement handle of FIG. 1 illustrated with additional subject matter in broken lines;

FIG. 7 is a front view thereof;

FIG. 8 is a rear view thereof;

FIG. 9 is a right side view thereof, the left side view being a mirror image of the right side view;

FIG. 10 is a top view thereof; and

FIG. 11 is a bottom view thereof.

FIG. 12 is a front, perspective view of the kitchen implement handle of FIG. 1 illustrated with additional subject matter in broken lines;

FIG. 13 is a front view thereof;

FIG. 14 is a rear view thereof;

FIG. 15 is a right side view thereof, the left side view being a mirror image of the right side view;

FIG. 16 is a top view thereof; and

FIG. 17 is a bottom view thereof.

FIG. 18 is a front, perspective view of the kitchen implement handle of FIG. 1 illustrated with additional subject matter in broken lines;

FIG. 19 is a front view thereof;

FIG. 20 is a rear view thereof;

FIG. 21 is a right side view thereof;

FIG. 22 is a left side view thereof;

FIG. 23 is a top view thereof; and,

FIG. 24 is a bottom view thereof.

The features shown in broken lines are portions of the kitchen implement handle or environmental subject matter to the kitchen implement handle forming no part of the
